UNITED STATES PATENT OFFICE.

ABRAHAM L. SMITH, OF NEW YORK, N. Y., ASSIGNOR OF ONE-HALF TO ORILLA M. SMITH, OF NEW YORK, N. Y.

CATAMENIAL-SACK SUPPORTER.

Application filed November 16, 1922. Serial No. 601,743.

To all whom it may concern:

Be it known that I, ABRAHAM L. SMITH, a citizen of the United States, residing in the borough of Manhattan, in the city, county, 5 and State of New York, have invented certain new and useful Improvements in Catamenial-Sack Supporters, of which the following is a full, clear, and exact specification.

10 This invention relates to catamenial sack supporter, and my improvement is directed to a novel form of belt possessing the following characteristic features and advantages.

15 (1) The belt is provided with means for its adjustment to any degree about the waist of the user.

(2) Though composed of elastic webbing and of considerable width with a rear strap 20 slidably adjustable by a loop thereon, the belt is prevented from sagging or dragging by reason of stiffening means located within the loop.

(3) The front portion of the belt is provided with a tab of inelastic material having a strap depending therefrom.

(4) Buckles of specially devised form are carried by the front and rear straps, and are adapted to lie flat against the body of the 25 wearer, serving to frictionally engage and retain the towel to be used with the device.

Other features and advantages of my invention will hereinafter appear.

In the drawing:—

30 Figure 1 is a perspective elevation of my invention.

Fig. 2 is a partial view, enlarged, showing the back portion of the slidable loop with the belt engaged by the stiffening means 35 therein.

Fig. 3 is a section on the line 3—3 of Fig. 1, and

Fig. 4 is a section on the line 4—4 of Fig. 1, illustrating the means whereby a 40 towel is engaged by a buckle.

In said figures, 1 indicates a belt composed of elastic webbing. This belt may be of considerable width to add to the comfort with which it may be worn. One end of the 45 belt is sewn to one side edge 2 of a front tab 3 of non-elastic material, which has a pendent portion 4; and to this portion 4 is sewn a strap loop 5, as of elastic webbing, with which is engaged a buckle 6. 50 The opposite side edge 7 of the tab 3 is formed

into a loop which engages a buckle 8, whose central bar 9, which is provided with retaining teeth 9', receives the folded over, free end 10 of the belt, this free end passing thence under the forward bar 11 of the buckle, to thereby frictionally retain the belt fastened when drawn about the wearer's waist. The free terminal portion of the belt may be confiningly introduced beneath a strap 12 which is slidably fitted over the belt.

Slidably adjustable over the belt, at its rear portion, is a strap member composed of a double length of elastic webbing, which is sewn transversely intermediate its 70 length, as at 13, to thereby constitute the upper loop 14, by which the member is fitted over the belt, and the lower pendent loop 15, in whose terminal portion a buckle 16 is engaged.

75 Spread within the loop 14 is a shape maintaining device composed of flat, stiff material, having the central vertical bar 17 and the opposite, side bars 18, 18 in spaced relation therewith. The bars 17 and 18 are 80 connected at top by a bar 19, and at bottom by the angularly disposed arms 20, 20, which diverge downwardly from their junction with bar 17 to their respective points of connection with the bars 18. The bar 17 terminates at its lower end in the points or teeth 21 which lie within the horizontal plane forming the base line of bars 18.

85 This stiffening member is of sufficient height to fit snugly within the loop 14, to prevent it from wrinkling. The belt 1 is threaded between the bars 17 and 18, in the manner indicated in Fig. 2, and, when the loop is suitably adjusted upon the belt, as by sliding it thereover, the belt in this action 90 being drawn through the bars 17, 18, then the teeth 21 are pressed into engagement with the material of the belt, to maintain the extended width thereof, for which purpose the teeth may be bent slightly in the direction of the belt, whereby the loop becomes localized upon the belt, and will not shift from its set position.

95 The buckles 6 and 16 are alike, each having a central bar 23 and opposite side bars 100 24, 25, in spaced relation therewith.

The bar 24 is adapted to lie upon the outer surface of its strap and is provided with rearward teeth 26; while the forward bar 25 projects beyond the end of the loop.

Hence, secure frictional engagement of a towel, as 27, is had by each of the buckles, by passing a towel end first under bar 25 and out between it and the strap end, thence 5 under bar 24, and, drawing it over the teeth thereof for return again under bar 25, in the opposite direction, leaving the towel end projected beyond bar 25. In this action the towel is to be drawn to a desired moderate 10 degree of tension, and it will be firmly held in position by its frictional engagement in the buckle, aided by the support it receives against the body of the wearer.

With the means of towel engagement by 15 the front and rear buckles it will be readily appreciated that adjustment thereof can be quickly and conveniently effected to apply the towel with the requisite degree of tension, and to loosen it, while in use, when desirable. Also it will be found that with my 20 improved connecting means the towels may be changed with great facility.

Variations within the spirit and scope of my invention are equally comprehended by 25 the foregoing disclosure.

I claim:—

1. In a catamenial sack supporter, in combination, a relatively broad belt having a fixed pendent tab at its forward portion, said tab carrying towel engaging means, a 30 looped member slidably adjustable upon the belt at its rear portion, said looped member also carrying towel engaging means, and a relatively stiff member fitted within said looped member to maintain its form, said 35 relatively stiff member having means of removable engagement with the belt.

2. In a catamenial sack supporter, in combination, a relatively broad belt, a towel engaging strap having a loop by which it is 40 slidably adjustable on the belt, a brace of stiff flat material fitted within the loop, to maintain its height, means in said brace for the slideable reception of the belt, and means upon the brace for removably engaging the 45 belt to localize the strap thereon.

Signed at the borough of Manhattan, in the city, county and State of New York, this 10th day of November, 1922.

ABRAHAM L. SMITH.
